UNITED STATES PATENT OFFICE.

GEORGE T. BYERS, OF NEW YORK, N. Y.

DESIGN FOR A HOLDING-CLIP FOR PENS AND PENCILS.

45,102.

Specification for Design.

Patented Jan. 6, 1914.

Application filed April 14, 1913. Serial No. 761,069. Term of patent 7 years.

To all whom it may concern:

Be it known that I, GEORGE T. BYERS, a citizen of the United States, residing at New York, in the county of New York and State of New York, have invented a new, original, and ornamental Design for a Holding-Clip for Pens and Pencils, of which the following is a specification, reference being had to the accompanying drawing, forming part thereof.

The figure is a perspective view of the design, the pen or pencil being indicated in dotted lines.

The design consists in the formation of the clip, in which a serpentine form is utilized to conform with all the mechanical requirements of the clip as shown.

I claim:

The ornamental design for a holding clip for pens and pencils, as shown and described.

GEO. T. BYERS.
